THROTTLING CALORIMETER

Blair H. Stone, El Reno, Okla.

Application October 14, 1935, Serial No. 44,995

5 Claims. (Cl. 73—192)

The invention relates to improvements in steam measuring devices generally and more particularly to a throttling calorimeter thereof.

An object of the invention is to provide a throttling calorimeter with means to indicate, by direct reading and/or visual and/or audible signals, the quality of steam in percent of moisture content.

Another object has to do with the provision of the modified throttling calorimeter as aforesaid and which is adapted to indicate the percent of moisture content of steam at a point remote from the source of steam generation.

Still another object resides in the provision of a measuring device of this class which will operate for either continuous or intermittent indication of the percent of moisture content of steam, the operation thereof being based on the principle of the throttling calorimeter.

Yet another object lies in the provision of a throttling calorimeter wherein a steam sample within the same is surrounded by steam at vessel pressure until it reaches the throttling orifice.

A further object of the invention is to provide a means or device of the class mentioned and wherein the indications of percent of moisture content of steam are obtained through the medium of a temperature gage of the Bourdon tube type which is actuated either by the vapor tension of a liquid or by the expansion of a gas.

With these and other equally important objects in view, the invention resides in the certain new and useful combinations, constructions and arrangements as will be hereinafter more fully described, set forth in the appended claims, and illustrated in the accompanying drawing, in which:

Figure 1 is a side elevation of the device, in accordance with the instant invention,

Figure 2 is a right hand end elevation thereof, with the indicator gage and electrical circuits removed,

Figure 3 is a vertical longitudinal section taken on the line 3—3 of Figure 2, and

Figure 4 is a plan view of the Bourdon tube and its associated contacts and wires of the electrical indicating or signal circuits, with the enclosing casing thereof removed.

Referring to the drawing, wherein like characters of reference designate corresponding parts in the several views thereof, the embodiment of the invention, as is shown therein by way of example only, is constituted generally in a throttling calorimeter A to receive a sample of steam

from a source or vessel (not shown); a gage B having connection with the calorimeter A and its dial calibrated to give readings in percent of moisture content of steam; electrical circuits C leading from controlling contacts within the gage B to audible and visual signal instrumentalities which operate at predetermined settings of the gage to indicate certain percentages of the moisture content of the steam under test; and an automatic boiler blow-down valve D which is cooperative with one of the said signal circuits.

The throttling calorimeter A is comprised in an outer casing or jacket 10 which is substantially cylindrical in form and has its ends closed by plates 11 and 12. The plate 11 is preferably screw threaded into the casing or jacket end and has an oppositely nippled opening at its center, with the outer nipple portion 13 externally screw threaded, as at 13a, for its attachment to the steam source or vessel from which samples are to be taken for test. The inner nipple portion 14 is in connection with the end plate 15 of a throttling chamber or barrel 16 which is positioned within the casing or jacket 10 at the approximate center thereof.

The casing or jacket 10 is provided with an opening in its top side for the packing of its interior, about the throttling chamber or barrel 16, with a heat insulating material 17; the said opening being normally closed by a removable cover 18 which is held in place by screws or the like 18a.

Extending inwardly of the bore of the nipple portions 13—14 is a sampling nozzle 19 which is in the form of a length of metal tubing or pipe having its outer end closed and its inner end open and internally screw threaded for attachment to an orifice plug 20; the latter, in turn, being screw threaded outwardly of an opening in the center of the end plate 15 of the throttling chamber or barrel 16. The outer end portion of the nozzle 19 is provided with side perforations 19a for the intake of steam there-through and its subsequent passage through the nozzle to the orifice in the plug 20.

The throttling chamber or barrel 16 is preferably cylindrical in form and has one end in screw threaded connection with the end plate 15 and its other end in similar connection with an end plate 21 carried at the inner end of the inner nipple portion 24 of an opening in the end plate 12 of the casing or jacket 10. Steam admitted to the throttling chamber or barrel 16 is exhausted therefrom outwardly through a nippled outlet 22, projecting from the lower side 55

of the chamber or barrel toward the end thereof opposite the orifice plug 20, and from thence outwardly through a nipped outlet 23 projecting through the wall of the casing or jacket 10.

5 The end plate 12 has its central opening in line with the bores of the inner nipple portion 24 and an outer nipple portion 25 and with the orifice in the plug 20.

Passing inwardly through the bore 26 thus provided is an orifice plug rod or needle valve 27, the inner end of which is tapered off or pointed, as at 27a, for cooperative engagement with the orifice in the plug 20. A coiled spring 28 is engaged over the inner end of the valve rod 27 and is compressed thereon, between the end plate 21 and a shoulder 29 on the valve rod adjacent the pointed or valve end thereof, to normally tension the latter in closing engagement with the plug orifice.

10 20 The outer nipped portion 25 of the end plate 12, of the casing or jacket 10, is provided with a depression in its end face to receive a packing 30 which is held in place by a jam nut 31 and compressed thereby about the valve rod 27.

25 30 Attached to the outer side of the end plate 12, by means of a screw or the like 32, is an angled bracket 33 which carries a cylinder 34 at its free end. The cylinder 34 has its bore 34a disposed in line with the bore 26 passing through the nipple portions 24—25 and the end plate 12 to receive the outer end of the valve rod 27, which end is arranged in screw threaded connection with a piston 35. The inner end of the cylinder 34 is provided with a packing 36 which is compressed in place about the valve rod 27 by means of a jam nut 37.

An operating fluid for the piston 35 is admitted to the bore 34a, of the cylinder 34, through a screw threaded connection 38 and effects a movement of the piston and the valve rod in a direction against the tension of the spring 28 to open the orifice in the plug 20 for admitting steam from the nozzle 19 to the interior of the throttling chamber or barrel 16.

40 45 Positioned within the throttling chamber or barrel 16 is an annular bulb or chamber 39 which is stationarily encircled about the spring 28 and the valve rod 27 and has connection with a conduit or tubing 40 leading outwardly of the throttling chamber or barrel through the end plates 21 and 12 to a point of connection with an inlet 42 of the casing 41 of the gage B.

The gage B is suitably emplaced apart from the calorimeter A and has a Bourdon tube within 45 50 55 in the casing 41 and connected at one end to the inlet 42. Cooperative with the tube 43, within the casing 41, is a usual operating means (not shown) for the shaft 44 of an index or pointer 45 which overlies a dial 46 mounted on one of the outer sides of the casing.

The dial 46 has its face provided with two concentric scales of graduations 47 and 48, the outer scale 47 being calibrated to read in percent of moisture content of the steam sampled 60 65 and the inner scale 48 in degrees of steam quality.

70 Cooperative with the Bourdon tube 43, within the casing 41, is an electric switching means for controlling external indicating circuits C. The indicators or signals in these circuits are for the purpose, one to indicate satisfactory steam quality and the other an unsatisfactory steam condition, as will later be apparent. Cooperative with one of these circuits is the automatic blow-down valve D, which will perform its usual func-

tion in steam boiler operation upon the alternate closing and opening of the circuit with which it is cooperative by the switching means under the control of the gage B.

The switching means is comprised in a link 5 49 connecting the gage tube 43, through pivot connection 50, with the index or pointer operating means. This link 49 is preferably made of an insulating material, such as hard fibre or the like, and is pivoted, as at 50, to the free end 10 of the gage tube 43, somewhat after the manner shown in Figure 4, and carries a switch arm 51 in angular relation thereto for wiping cooperation with a pair of electric contacts 52 and 53 mounted on an insulated support 54. The contacts 52 and 53 are spaced apart from each other and from adjacent sides of the switch arm 51. The support 54 is adjustably fastened in place to the gage casing 41 by means of a slot 55 engaged by a screw 56.

20 This switching means is connected to the external indicating circuits C and the automatic blow-down valve D, by conductors leading outwardly of the gage casing 41 through a bushing or nipple 57; the circuits being as follows:—A 25 conductor 58 from the switch arm 51 to one terminal of a current source or battery 59; a conductor 60 from switch contact 53 to one side of the electromagnet 61 which has its other side connected by a conductor 62 to one side of a 30 signal lamp 63. A conductor 64 leads from the other terminal of the current source or battery 59 and directly connects the other side of the signal lamp 63 and also connects one side of a second signal lamp 65 by a branch conductor 66. 35 An audible signal device, such as an electric bell or buzzer 67, has one of its terminals connected by a conductor 69 to the battery conductor 64 at a point thereon between the points of connection of the same with the signal lamps 63 and 65, and its other terminal by a conductor 68 to the conductor 60 at a point thereon between the switch contact 53 and the electromagnet 61. The switch 52 is directly connected to the remaining side of the second signal lamp 65 by a conductor 70. 40 45

In the operation of the apparatus or device thus provided, the calorimeter A is attached to the steam source or vessel (not shown) from which steam is to be sampled at the threaded 50 nipple 13, when steam will pass into the nozzle 19 at the perforations 19a. The gage B will then be placed in a convenient position, either at the point of temperature or at a point remote therefrom, and, if the electrical indicating circuits C 55 are employed, they will also be suitably located to meet the requirements of the installation. Upon the placing of the calorimeter A the threaded connection 38 will be coupled to a source of fluid pressure (not shown) for the actuation of the piston 35. With the calorimeter A installed as stated, the nozzle 19 is projected well into the steam mass and is surrounded at all times by steam which is of the same temperature and pressure as that of the steam sample 60 65 passed through the nozzle to the throttling orifice.

70 Now, by admitting pressure to the cylinder 34, the piston 35 will be forced to the right and thereby exert a pull on the rod 27 and withdraw 70 the valve point 27a from the orifice in the plug 20. This movement of the piston and rod will act to compress the spring 28 between the shoulder 29 and the end plate 21, so that the spring 75 will function to return the rod and piston to

normal position, with the valve point 21a again closing the orifice in the plug 20, when the pressure is released from the piston 35.

Upon the opening of the orifice in the plug 20, by the withdrawal of the valve point 21a therefrom, steam will pass from the nozzle 19 into the throttling chamber or barrel 16 and about and through the open center of the bulb 39 to the exhaust port nipples 22 and 23. In the passage of the steam sample around the bulb 39, heat therefrom will be transferred to a fluid in the bulb and the conduit or tubing 43 for the actuation of the Bourdon tube 43 in the gage casing 41; the pressure of this fluid changing with temperature variations of the steam sample.

In the instant disclosure of the invention, a vapor tension type of gage has been described and shown, but it will be obvious that other types of dial thermometers, for instance, a gas filled type thereof, may be substituted therefor, if and when desired. The gage is adjustable for various pressures at its linkage, for instance, from an initially set pressure indication, the linkage will be shortened or lengthened respectively for an increase or a decrease in indicated pressure, each adjustment being for a temperature change representative of a one percent change of the pointer on the dial of the gage.

Further in the operation of the apparatus or device, if and when the switching means and the electrical indicating circuits C, together with the automatic blow-down valve D, are employed, upon movement of the Bourdon tube 43, to swing the link 49 on the pivot 50', for instance to cause the switch arm 51 to wipe over the contact 53, the circuit will be closed on the current source or battery 59, the electromagnet 61, the signal lamp 63, and the bell or buzzer 67; the current passing from the positive terminal of the current source or battery 59 by way of conductor 58, switch arm 51, contact 53, conductor 60, electromagnet 61, signal lamp 63, and conductor 64 to the negative terminal of the current source or battery 59. Also, current will flow from conductor 60 by way of conductor 68, the bell or buzzer 67, and conductor 69 to the current source or battery return conductor 64. In the other or reverse movement of the Bourdon tube 43 and the link 49, the switch arm 51 will wipe over contact 52 and close the circuit on the current source or battery 59 and the signal lamp 65 only; the current now passing from the positive terminal of the current source or battery 59 by way of conductor 58, switch arm 51, contact 52, conductor 70, signal lamp 65, and conductors 66 and 64 to the negative terminal of the current source or battery 59. The signal lamps 63 and 65 will be colored and preferably one different from the other. Thus, both visual and audible signals or indications will be given to the operator making a test on a given steam source.

With the alternate closing and opening of the circuit at switch contact 53, the electromagnet 61 will actuate the blow-down valve D correspondingly to open and close positions, and the operation of the valve will be adjustable to percent moisture desired, according to the setting of the switch contacts 52 and 53 with respect to the switch arm 51.

Considering for the moment the principle of operation of a throttling calorimeter, steam passing through an orifice into an enlarged space, i. e., a space large enough that the resultant velocity is low, retains practically all the heat energy that would make up velocity energy, and

this retained heat energy acts to superheat the steam. The throttling calorimeter therefore measures this superheat and from thermometer readings this steam quality or percent moisture is calculated. The instant device eliminates all necessity for the use of ordinary mercury thermometers and allows percent moisture (or steam quality 100%-% moisture) to be readily ascertained by direct reading from a Bourdon type of pressure gage, or from an electrical meter (not shown), if the latter be substituted.

An illustrative problem in the use of the apparatus or device, in accordance with the present invention and by reference to the Marks & Davis Steam Tables which show that steam at 250# gage has 1202.4 B. t. u., per pound and steam at atmospheric pressure (14.7# gage) has 1150.4 B. t. u., per pound and a temperature of 212 degrees F., is stated as follows:—250# gage steam through throttling calorimeter to atmospheric pressure. Solution:

Item 1.—Heat per pound in B. t. u., available for super-heating (sample dry, without moisture):—1202.4 B. t. u., at 250# gage minus 1150.4 B. t. u., steam at 0#, or atmosphere gives 52.0 B. t. u., per pound, available for superheating.

Item 2.—Specific heat of steam at atmospheric pressure (from tables):—.47 B. t. u., required per pound per degree F.

Item 3.—Maximum possible superheat in calorimeter, with initial steam 250# gage:—Item (1) 52.0 B. t. u., divided by Item (2) .470 B. t. u., equals 110.5 degrees F.

Item 4.—Maximum possible temperature in calorimeter, with initial steam 250# gage:—atmospheric temperature of steam plus superheat equals total calorimeter temperature, hence 212 degrees F., plus Item (3) 110.5 degrees F., equals 322.5 degrees F.

Item 5.—Latent heat of evaporation 250# gage steam (Marks & Davis Tables) is 821.5 B. t. u., and equivalent to 100% moisture.

Item 6.—1% moisture in steam at 250# gage is therefore Item (5) 821.5 B. t. u., divided by 100, which equals 8.215 B. t. u.

Item 7.—Steam at 250# gage with 1% moisture has a B. t. u., content of 1194.18 B. t. u., (1202.4 B. t. u., minus, Item (6) or 8.215 B. t. u.).

Item 8.—1% moisture in steam lowers superheat temperature equivalent to Item (6) 8.215 B. t. u., divided by Item (2) .47 B. t. u., which equals 17.45 degrees F.

Item 9.—Maximum operating range of calorimeter in percent moisture equals Item (3) 110.5 degrees F., divided by Item (8) 17.45 degrees F., or 6.34 percent moisture.

However, it has been determined that a readable range of the calorimeter can be extended to a maximum of about 11% by changing atmospheric pressure to a low vacuum.

In the present instance, the Bourdon tube gage is a thermometer actuated by superheat and it is calibrated to read in percent moisture or steam quality, and it is to be noted that, as shown, the gage index or pointer 45 swings in reverse to the ordinary direction of movement thereof, and that the zero of the scale 47 is at the opposite end from which the index or pointer comes to rest, or, in other words, zero percent moisture represents the maximum possible temperature of the superheat of the steam sample. As the percent moisture increases less superheat occurs and at 6.3% moisture and 250# gage, just enough heat is available to give the throttled sample a temperature of 212 degrees F., and the index or pointer 45 moves

ment will start at the maximum measuring range of the gage corresponding to atmospheric pressure. In other words, the calibrated part of the swing of the index or pointer 45 is between the temperatures 212 degrees F., and maximum superheat 322.5 degrees F., which represents a range of 6.3% moisture. For normal temperatures, say 60 degrees F., the index or pointer 45 comes to rest off the scales, i. e., the space between 5 the point of rest and that where the graduations begin, which space represents a temperature range of from 60 degrees F., to 212 degrees F.

It is also to be here noted that, since each 10 steam pressure has different heat content and latent heat of evaporation, a dial calibrated for one pressure is not entirely correct for any other pressure. The deviation from accuracy is not 15 large, with reference to steam pressure range permitted on a boiler in operation that does not fluctuate over 25# gage. Many boilers, however, 20 do not fluctuate over 10# gage and therefore, for all practical purposes, the instant apparatus or device will be entirely satisfactory. The error in reading, when the pressure drops, for instance, 25 to 175# gage and reading is taken from a 250# scale, is .66 of 1% moisture.

Without further description, it is thought that the features and advantages of the invention 30 will be readily apparent to those skilled in the art, and it will of course be understood that changes in instrumentalities employed and minor details of construction and arrangement may be resorted to without departing in any way from the spirit of the invention, or its scope as claimed.

35 Having thus fully described my invention, what I claim is:

1. A throttling calorimeter comprising a heat insulated chamber having an intake orifice and an exhaust port, a hollow member within said 40 chamber between the intake orifice and the exhaust port, said member containing a fluid sensitive to variations in temperature of a heated fluid passed through the chamber for test, means located exteriorly of the chamber for indicating

the variations in transfer of heat from the heated fluid to the fluid within said member, a normally closed valve within the chamber to control ingress of the heated fluid to be tested, and a pressure operated means exteriorly of the chamber 5 and having connection with said valve to actuate it to open position as and when required.

2. A throttling calorimeter comprising a heat insulated casing, a throttling chamber within said casing and having an intake orifice opening 10 outwardly of the casing, a sampling nozzle projecting from said casing for conveying steam to said orifice, a rod extending inwardly of said casing and into said chamber and having a tapered end to engage in said orifice, spring 15 means normally urging said rod to force the tapered end thereof into closing engagement with said orifice, and pressure operated means for actuating said rod to withdraw the tapered end thereof from said orifice for admitting steam 20 therethrough from said sampling nozzle.

3. The calorimeter as set forth in claim 2, wherein said pressure operated means is comprised in a cylinder at the outer side of the said casing and a piston on the outer end of said rod, 25 the cylinder having an inlet for the pressure to actuate the piston.

4. The calorimeter as set forth in claim 2, 30 wherein a thermometer bulb is emplaced within said throttling chamber in direct contact with the superheated steam therein, and a dial type of thermometer is connected to said bulb and located exteriorly of the said casing to indicate the quality of the steam.

5. The calorimeter as set forth in claim 2, 35 wherein a thermometer bulb is emplaced within said throttling chamber in direct contact with the superheated steam therein, and a dial type of thermometer is connected to said bulb and located exteriorly of and remotely from said casing 40 to indicate the quality of the steam, said thermometer being calibrated in percent moisture of the steam sample.

BLAIR H. STONE.
